UNITED STATES PATENT OFFICE

ROLLO F. WALTERS, OF DETROIT, MICHIGAN, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

SEPARABLE FASTENER

Original application filed July 24, 1924, Serial No. 727,960. Divided and this application filed May 28, 1928. Serial No. 281,181.

This invention aims to provide an improved separable fastener particularly, though not exclusively, useful in connection with upholstery installations.

5 This application is a division of my prior application, Serial No. 727,960, filed July 24, 1924.

In the drawings, which illustrate a preferred embodiment of my invention:—

10 Figure 1 is an elevation view of a door of an automobile showing the frame and the stud-receiving apertures therein;

Fig. 2 is an elevation view of the backing of an upholstered part, showing the studs secured thereto;

15 Fig. 3 is a section through the door frame and upholstered part, showing the stud partly in elevation;

Fig. 4 is a fragmentary view of a portion 20 of the upholstered part as viewed from that side thereof at which the stud heads are presented;

Fig. 5 is an elevation view of the preferred form of shiftable stud; and

25 Fig. 6 is an enlarged section on the line 6—6 of Fig. 4.

Referring to the form of my invention, as illustrated by the drawings, I have shown an automobile door, an upholstered part for 30 covering the inside of the door and separable fastener means for securing the upholstered part to the door.

Heretofore the fastener elements have been rigidly secured to the frame of the door and 35 to the upholstered part and some difficulty has been encountered in registering the fastener elements on the upholstered part with the fastener elements on the door frame. To remedy this difficulty, I have provided, as 40 illustrated, a plurality of shiftable studs located on one of the parts for engagement with rigid socket means on the other part, thereby permitting perfect alignment of any of the studs with their cooperating sockets.

45 Thus, the upholstered part may be secured

to the door without difficulty and the edges of the upholstered part may be properly "lined up" with the edges of the door.

Referring now to Figs. 2, 3, 4 and 5, I have shown an upholstered part which includes a backing 1 of relatively stiff material such as cardboard or the like, constituting a form which is provided with a plurality of holes 2 adjacent the edges thereof, and a plurality of shiftable studs cooperating with the 50 holes 2. These studs are secured to the front face of the backing by a casing or attaching plate 3, and their heads are presented, through the holes 2, at the opposite face thereof for cooperation with the stud-receiving means on the part to be upholstered.

55 In the form of my invention illustrated by the drawings each stud is provided with an attaching plate, herein serving as a base loosely carrying the stud to permit shifting of the stud without corresponding shifting of the base. Two types of attaching plates are shown, each providing portions overlying and underlying the base flange of the 60 stud.

70 Each stud is assembled with its attaching plate 3 at the factory, thereby to provide a stud unit which may be easily, quickly and accurately secured in the proper relation to a hole 2 in the backing of the upholstered part, by the use of proper dies for registry with the aperture and for holding the stud-attaching plate. The stud and attaching plate, I term collectively a stud unit.

75 The socket-engaging part of the stud unit is pressed from a single sheet of metal and is provided with a base flange 4, a shank portion 5, a head 6 and a neck 7 between the head and shank portion. The head, neck and shank portions are rendered resiliently contractible by a plurality of slots, herein shown as three, which preferably, as illustrated, extend to or slightly into the base of the stud.

80 The casing or attaching plate 3, which is pressed from a single sheet of metal, presents 85

a smooth bottom, an upstanding peripheral wall 8, a plurality of stud-retaining prongs 9 and attaching prongs 10 extending from the wall 8.

5 The stud may be assembled with the attaching plate by placing the base portion 4 of the stud into the recess provided by the upstanding wall 8 and then bending inwardly the stud-retaining prongs 9 until they overlie the base of the stud, thereby holding the stud and attaching plate in assembled relation even prior to assembly with the backing, as best shown in Fig. 6.

As illustrated, the diameter of the base portion 4 of the stud is less than the diameter of the attaching plate and the short prongs 9 do not extend to the shank portion 5 of the stud, thus permitting free lateral movement of the stud in any direction relative to the attaching plate.

20 Assembly of a stud with the backing 1 is effected preferably by dies (not shown) which align the attaching plate 3 with a hole in the backing and force the attaching prongs 10 through the backing, where they are upset against the opposite face thereof, as best shown in Figs 4 and 5.

The holes in the backing are somewhat larger in diameter than the diameters of the shanks of the studs, thereby permitting sufficient free movement of the studs in any lateral direction relative to the backing to compensate for variation in the exact positioning of the stud-receiving apertures in the door or other part to be covered by the upholstery installation.

25 The advantages of securing the stud to the front face of the backing instead of the back face are, firstly, that for the same projection beyond the face of the installation, a shank portion 5 of considerably greater length may be used, thereby affording an opportunity for greater resiliency of the head of the stud, and, secondly, that the strain exerted on the 30 stud when it is separated from the socket to which it is secured, is taken by a considerable area of the backing and not by the prongs, as when the studs are secured to the back face of the backing. The smooth bottoms of the 35 studs, as shown in Figs. 3, 4, 5 and 6, promote smoothness of the covering 11 in completed upholstery installation and permit the studs to be pressed into engagement with their sockets without injury to the covering 11, which conceals the studs from view.

40 When the studs are all secured to the backing 1, a padding 12 is placed over the backing to improve the appearance of the edge of the upholstered part and to provide a surface which is generally in line with the bottoms of the stud-attaching bases. Thus the covering 11 of cloth, leather or the like is stretched smoothly and evenly over the outer face of the backing and its edges are secured 45 to the inner face of the backing, thereby pro-

viding a neat upholstered finish covering the outer face of the backing.

50 The door 13, to which the upholstered part is secured, may be, as illustrated, formed of sheet metal and preferably presents at the inner face thereof, adjacent the periphery, a metal frame 14 having a plurality of stud-receiving apertures 15 punched or drilled therethrough for reception of the heads of the studs located on the upholstered part.

55 The upholstered part may be applied to the door by pressing the heads 6 of the studs into the stud-receiving apertures, thereby holding the upholstered part tightly against the frame of the door.

60 If any stud does not register with its co-operating aperture in the frame, the stud may be shifted, by the use of a suitable tool inserted between the frame and the upholstered part, until it is in proper position to be pressed into engagement with its cooperating aperture. Thus adjustability of the positions of the studs is particularly important where the sheet metal door covering and the flanges providing the frame 14 are integral, the flanges bent over after the holes therein are punched. In such case, because of unequal stretching of the metal, the stud-receiving apertures are exceedingly likely to be slightly out of their desired positions. However, the 65 capability of the studs to shift is desirable, even when the door frame or other carrying part is drilled in a jig, and the backing punched in a similar jig. Where the upholstered part is used as a covering for something other than a door, and particularly 70 where it is used with a heavily padded covering, the shiftability of the studs becomes even 75 more essential.

80 The illustration of my invention and the description thereof is merely for clarification and not for limitation, my invention being best defined in the appended claims.

Claims:

85 1. A fastener unit comprising, in combination, an attaching part, a number of attaching prongs spaced substantial distances apart and formed integral with and extending from said attaching part for piercing a support to secure the fastener unit thereto, a shiftable fastener part assembled with said attaching part and extending in the same direction as said attaching prongs, and means provided by the fastener unit to secure the attaching part and fastener part together 90 while permitting transverse shifting of the fastener part in any direction transverse to the axis of the fastener unit.

95 2. A stud unit including a casing having a peripheral wall, a wall extending inwardly at right angles from said peripheral wall, a laterally shiftable stud having a base located in said casing, said stud having a head and a neck extending away from said base, said base being smaller in diameter than the space 100

enclosed by said peripheral wall to permit the lateral shifting of the stud, attaching prongs spaced substantial distances apart and extending from said peripheral wall for securing the stud unit to a support and ears extending inwardly from said peripheral wall at points located between the attaching prongs, said ears extending over one face of the base of the stud to assist in holding the stud in assembly with said casing.

10 In testimony whereof, I have signed my name to this specification.
